UNITED STATES PATENT OFFICE

EROB J. LINDGREN, OF BUFFALO, NEW YORK, ASSIGNOR TO NIAGARA MACHINE AND TOOL WORKS, OF BUFFALO, NEW YORK, A CORPORATION OF NEW YORK

AUTOMATIC PUNCH PRESS

Application filed December 30, 1929. Serial No. 417,353.

This invention relates to a punch press and more particularly to an automatic feed for feeding a strip of metal to and through the punch press dies and including feeding devices, gaging devices, end trimming devices, guiding devices, gripping and converging devices and scrap cutting devices, all of which are synchronized to the operation of the punch press itself so that the entire operation of the various mechanisms is automatic.

One of the objects of this invention is to provide a device of this character which operates automatically to feed strips of comparatively heavy gage sheet metal in immediate succession to a punch press which punch press is synchronized with the movement of the feeding mechanism and punches the predetermined number of pieces from each strip as it is fed.

A further object is to provide such a mechanism through which a continuous stream of blank strips is fed in which provision is made for gaging or registering each strip fed so that an exact number of perfect pieces is punched from each strip, provision in particular, being made to prevent successive strips from overlapping one another or from being spaced apart since such displacement would result in a piece of unpunched metal at one end of the strip and an imperfect punching at the other end of the strip.

A further object is to trim the trailing end of the strip being punched to an exact length and to position or gage the advancing end of the strip being fed with reference to this trimmed end so that the strips pass through the press substantially in end-to-end relation and so that there is no danger of one overlapping the other.

A still further object is to provide a simple and reliable means whereby those mechanisms which operate every time a piece is punched from the strip and several times upon each strip such as the strip advancing mechanism and the scrap cutter, are synchronized with those mechanisms which operate only once on each strip of metal, such as the initial feed, gaging and end trimming mechanisms.

Another object is to provide a simple mechanism for shearing the scrap strips into small pieces so that the scrap is in convenient form to be transported from the machine.

Another purpose is to provide a machine in which delayed operations are effected in a simple and reliable manner so that at no time is there any danger of interference between mechanisms operating in sequence at about the same time or in their return movements.

A further purpose is to provide a machine of this character which is readily adjustable to different lengths widths and gages of strips or to produce any desired number or kinds of punchings.

Other aims are to provide such a mechanism which is reliable in its action and will function continuously to punch the desired number of pieces from the strips as the strips are continuously fed, which is simple in construction considering the function which it performs which is readily accessible for adjustment or repairs, which will not get out of order under severe and constant use and which will adapt itself to variation or irregularities in the blank strips.

In the accompanying drawings:

Figure 25 is a view similar to Fig. 24 showing the scrap metal cutting knives open.

Figure 26 is a fragmentary, vertical, longitudinal section taken on line 26—26, Fig. 24.

80 Figure 27 is a horizontal, longitudinal section taken on line 27—27, Fig. 5.

Figure 28 is a fragmentary, transverse section taken on line 28—28, Fig. 1, showing a 85 portion of the mechanism for opening and closing the sheet metal gripping and advancing fingers.

Figure 29 is a section taken on line 29—29, Fig. 1 of the same portion of the mechanism shown in Fig. 28.

Figure 30 is a fragmentary, vertical, longitudinal section taken on line 30—30, Fig. 29, of the same portion of the mechanism shown in Figs. 28 and 29.

95 Figure 31 is a fragmentary, vertical, transverse section taken on line 31—31, Fig. 5, showing particularly the means for vertically adjusting the gripping and advancing fingers to meet required conditions.

100 Figure 32 is a fragmentary, vertical, transverse section taken on line 32—32, Fig. 5, showing the cam drive and associated parts for the opening and closing of the gripping and advancing fingers.

105 Figure 33 is a fragmentary, longitudinal section taken on line 33—33, Fig. 2, showing the segment for reciprocating the gripping and advancing fingers and the adjusting means therefor.

110 Figure 34 is a vertical longitudinal section taken on line 34—34, Fig. 3, and showing the main clutch controlling the operation of the entire machine.

115 Figure 35 is a fragmentary enlarged section through the air buffer for cushioning the return movement of the feeding mechanism.

General organization

120 In its general organization, this invention comprises a continuously operated punch press of any suitable type, step by step means for gripping and advancing the blank strip of metal presented to the punch press so that successive pieces are formed and punched from the strip of metal, a feeding table on which the blank strips of sheet metal are laid preparatory to feeding, a feeding carriage and mechanism associated therewith which 125 is synchronized with the punch press and 130

upon the last advancing movement of the blank strip in the punch press to the dies moves the next succeeding blank strip on the table toward the press, a mechanism for positively rendering the feeding mechanism inoperative upon the completion of its feeding movement and also latching the feeding mechanism against accidental operation, a gage or guard mechanism which is arranged in the path of the strip being fed during the feeding operation and prevents the strip being fed from overrunning the strip in the press, an end trimmer which trims the trailing end of the strip of sheet metal in the machine at a proper place with reference to the dies so that the front end of the strip being fed, when released by said gaging means, will always be positioned immediately behind the trailing end of the strip being punched and without danger of overlapping, a shear for trimming the scrap strip into convenient lengths, and the mechanism required to operate the above mechanisms in proper synchronism and sequence to one another.

25 *The punch press*

The product of the present machine is shown by way of example as being a circular disc 40 each of which is provided with a plurality of perforations 41, although the invention is applicable to any form of punching. These are successively formed from successive blank sheets or strips 42 of metal, by first punching out the perforations 41 and then advancing the strip to bring the perforated part under a cutout die which punches out the piece. In the machine shown in the drawings thirteen punchings are made from a single strip and hence the ratio of operation between the strip feeding, shearing, and gage devices to the step by step advancing mechanism and the movement of the punch press will be one to thirteen, although it will be understood that this ratio is purely by way of example, the invention being applicable to any number of punchings from a strip, the ratio in operation of the said mechanisms being altered accordingly.

The punch press itself may be of any usual and well known construction, no claim being made to the punch press itself in the present invention but only in combination with the other mechanisms hereinafter described.

As shown in the drawings the moving parts of the press are carried by a frame 43 made of cast metal sections and carrying an electric motor 44 which drives the punch press and the mechanisms to which the present invention is directed. The motor shaft of the motor 44 carries a driving pulley 45 which drives a belt 46. This belt 46 passes around a belt tightener 47 and also around a large driven pulley 48. As best shown in Figs. 2 and 34 this driven pulley is mounted on a countershaft 49 which is suitably journaled

on the punch press frame 43 and at its opposite end drives a pinion 50 which meshes with a large main gear wheel 51, as shown in Fig. 3. This main gear is secured to the main crank shaft 52 of the punch press, which main crank shaft 52 is journaled centrally in the punch press frame 43.

As best shown in Fig. 5, the main crank shaft 52 is formed at its center to provide two offset cranks 53 each of which is connected to an upper platen holder 54 by an adjustable pitman or connecting rod 55. Each of these adjustable connecting rods or pitmen 55 preferably consists of an upper bearing member 56 connected to each crank 53, a lower bearing member 57 connected to a wrist pin 58 of the upper platen holder 54 and a screw 59 which is rotatably connected to the lower bearing member 57 and has a screw connection with the upper bearing member 56 so that upon turning each of these screws the platen holder is adjusted vertically. At its sides, this upper or movable platen holder 54 is formed to provide rails which are guided in guideways 60 in the punch press frame so that upon turning the crank shaft 52 the movable platen holder 54 is reciprocated vertically.

To the under side of the movable platen holder is removably secured an upper platen 61 and on the under side of this platen 61 are removably secured the male perforating die 62 and the male cutout die 63 as shown in Fig. 5 or the dies may be formed integrally with the platen as shown in Figs. 20 and 21. These male dies cooperate with a female perforating die 64 and a female cutout die 65, each of which is secured to a lower stationary platen 66 which is carried by a stationary platen holder 67 mounted on the bed of the punch press.

In order to control the operation of the punch press a main driving clutch and brake 68 is provided between the counter shaft 49 and the hub of the pinion 50 which drives the main gear 51. This clutch and brake 68 may be of any suitable type and as best shown in Fig. 34 the clutch is of the multiple disk type and the rotating clutch housing drum is engaged by brake arms which are operatively connected with the clutch mechanism so that when the clutch is opened the brake arms are applied to the brake housing drum and instantly stops the operation of the punch press. The clutch and brake 68 is controlled by a shipper rod 69 slidably mounted in the punch press frame. This shipper rod is connected to a lever 70 which is fixed to a rock shaft 71 journaled in a suitable bracket on the main frame and to the other end of this rock shaft 71 a lever 72 is secured. The lever 72 is connected by an adjustable rod 73 with an arm 74 fixed to a rock shaft 75. A hand lever 76 at the other end of the rock shaft 75 actuates the same to

open and close the clutch 68; and to operate the clutch from the other end of the feed table 77, a second hand lever 78 is arranged at the outer end of the feed table and connected indirectly to the hand lever 76 by a rod 79 so that when either of these hand levers are operated the clutch and brake 68 is actuated to connect or disconnect the power shaft 49 with the punch press and its associated mechanism.

The initial feeding mechanism

The blank strips 42 of metal to be punched are placed upon the feed table indicated at 15 77. This table is comparatively long and narrow and is composed of legs or standards 80, cross bars 81 connecting the upper ends of the legs 80, a top plate 82 on the cross bars 81 and a side rail 83 for holding the blank 20 strip 42 in position on the top plate 82. The top plate 82 is provided with a central longitudinal slot 84 through which the blank strip feeding carriage 155 works as herein-after described.

25 The blank metal strips 42 are placed upon the feed table 77 between the side rails 83 and on top of the trailing end of the blank strip which is being moved step by step through the punch press. As soon as a predetermined 30 number of punchings is made in the strip in the punch press, its rear end is trimmed off and the trailing strip placed on the feed table 77 is moved against a gage gate which properly positions it with reference to the trimmed 35 trailing end of the strip being punched and then releases it with the result that strips of accurate length are fed through the punch press in immediate succession. Since eight punchings are made from each blank strip 40 in the machine illustrated it is apparent that the feeding mechanism must operate once to every eight punching operations of the punch press. This initial feeding mechanism is preferably constructed as follows:

45 The numeral 85 represents a crank pin which, as best shown in Figs. 1, 3 and 5 projects outwardly from the end of the main crank shaft 52 of the punch press and is connected by a rod 86 with the end of a rock 50 arm 87 mounted on the end of a longitudinal rock shaft 88. As best shown in Figs. 11 and 18 at its opposite end a slotted rock arm 89 is keyed to this rock shaft 88 and adjustably secured to this slotted rock arm 89 is 55 an extensible connecting rod 90 of any suitable form. As best shown in Fig. 11, this connecting rod 90 is provided with a pin 91 at its lower end this pin being received in a recess provided at the end of a ratchet arm 60 92. To permit of detaching the ratchet arm 92 from the reciprocating connecting rod 90 the ratchet arm preferably carries a spring loaded plunger 93 which is normally held over the recess containing the pin 91 but upon 65 being pulled downwardly by means of the

finger knob 94 permits the connecting rod 90 and its pin 91 to be disconnected and rendered inoperative, thereby permitting of repairs or readjustments to the mechanism actuated by the ratchet without shutting down 70 the punch press completely.

The ratchet arm carries a movable pawl or dog 95 which engages the teeth of a ratchet wheel 96, this ratchet wheel being fixed to a ratchet shaft 97 on which the ratchet arm 92 is loosely carried. It is apparent that as the ratchet arm 92 is reciprocated with each reciprocation of the punch press mechanism, the movable pawl 95 is moved to advance the ratchet wheel 96 one or more teeth. The retrograde movement of this ratchet wheel 96 is prevented by a stationary pawl 98, and the number of advancing steps in each rotation of the ratchet wheel 96 correspond to the number of punchings made in each blank strip of metal. In the example illustrated eight punchings are made and consequently the ratchet wheel 96 would have eight, or multiples of eight, teeth so that it is turned one complete revolution while eight punchings 80 are made by the punch press.

Keyed to the other end of the ratchet wheel shaft 97 as best shown in Fig. 12 is a cam wheel 99, this cam wheel 99 having a projection 100 on one side which rides over a removable tooth 101 mounted in the lower arm of a bell crank lever 102. The tooth 101 of the bell crank lever is normally urged against the cam wheel 99 by a spring loaded pin 103 and when the projection 100 on the cam wheel 99 engages the tooth 101 it moves the upper arm of the bell crank arm 102 away from a clutch 104 so as to close the clutch.

This clutch, as best shown in Fig. 14 is 105 mounted on its driven shaft 105, its driving member comprising an oscillating sleeve 106. This sleeve is journaled in a supporting bracket 107 and journals the driven shaft 105. This driving sleeve is oscillated from the rock shaft 88, this driving sleeve being formed to provide arms 108 which are connected to a rock arm 109 on the rock shaft 88 by a link 110, as best shown in Fig. 13. It therefore follows that the driving sleeve 106 is oscillated each time a punching is made in the metal blank.

On the outer end of the driven clutch shaft 105 is keyed a collar 111 which is held in the shaft by a washer 112 and a screw 113. A transverse keyway 114 is formed in this collar 111, and in this keyway is slidably arranged a coupling key 115 which is normally urged against the end of the clutch driving sleeve 106 by a spring arranged in the keyway 114. In line with this key 115 the clutch driving sleeve 106 is provided with a notch 116, so that when the key 115 is released its spring urges it into the notch 116 and compels the driving sleeve 106, collar 111 and driven shaft 115 120 125 130 135 140 145 150 155 160 165 170 175 180 185 190 195 200 205 210 215 220 225 230 235 240 245 250 255 260 265 270 275 280 285 290 295 300 305 310 315 320 325 105 to oscillate in unison. The coupling key 115 is provided, with an outwardly projecting wedge shaped tooth 117, the inner face of which is engaged by a corresponding wedge 5 shaped tooth 118 mounted on the upper arm of the bell crank lever 102. It therefore follows that when the tooth 118 in the bell crank lever is held in the path of the tooth 117 on the coupling key 115 by the spring loaded pin 103, that the tooth on the bell crank lever 102 will retract the coupling key 115 and hence permit the driving sleeve 106 of the clutch to oscillate idly without affecting the clutch driven shaft 105. When, however, the projection 15 100 on the cam wheel 99 moves the tooth 101 of the bell crank arm 102 downwardly, the wedge or cam tooth 118 on the other end of this bell crank arm 102 is moved out of engagement with the sliding or coupling key 115, and this key moves into the notch 116 of the driving sleeve 106 of the clutch and forms a driving connection between this driving sleeve 106 and the driven clutch shaft 105. As the cam wheel 99 is rotated once for every eight operations of the punch press, it is apparent that the bell crank arm 102 is also tripped only once for every eight operations of the punch press and hence that the clutch 104 is closed so as to impart 20 an oscillation to its driven clutch shaft 105 only once in every eight operations of the punch press, this number corresponding to the number of punchings which have been assumed to be made in each metal blank 25 strip, 42.

Fixed to the driven clutch shaft 105 is a rock arm 120 which is connected to a vertically reciprocating bar 121, this bar preferably having universal connections at its opposite 40 ends. The lower end of the bar 121 connects with a rock arm 122 keyed in a transverse shaft 123 which is journaled in a pedestal 124 rising from the machine bed.

Guided in this pedestal 124 is a frame or 45 holder 125 which carries a rear end trim shear blade as hereinafter described and is reciprocated vertically from the shaft by a pair of rock arms 126 on the rock shaft 123 and links 127 connecting these rock arms 126 and the vertically reciprocating frame 125, as best shown in Fig. 10.

As best shown in Fig. 8, this frame or end trimmer blade holder 125 is provided at one side with an ear 128 which is pivotally connected to the upper end of a shipper rod 129. The lower end of this shipper rod connects with a rock arm 130 fixed to a rock shaft 131, this rock shaft being suitably journaled in supporting arms 132 and carrying a pair 55 of upwardly extending arms 133 which pivotally support one end of a vertically movable table 134, the other end of the table being supported by a pair of links 135 also mounted on the fixed supporting arms 132. 60

65 In the fixed supporting arms 132 between the

table supporting arms 133 and 135 is journaled a rock shaft 136 which has fixed thereto a rock arm 137, this rock arm 137 being connected to a rock arm 138 in the rock shaft 131 by a link 139. The rock shaft 136 also carries a rock arm 139 which extends in the opposite direction from the rock arm 137 and is pivotally connected to a shipper rod 140 having a slot 141 at its lower end. In this slot is arranged a pin 142 carried by a rock arm 143, which rock arm is fixed to a rock shaft 144, this rock shaft 144 also carrying a rock arm 145 which extends in the opposite direction from the rock arm 143. This last named rock arm 145 is connected by a link 146 with a rock arm 147 depending from a rock shaft 148. This rock shaft 148 also carrying a rock arm 149. The rock arm 145 and the link 146 are arranged to be moved upwardly beyond their dead center for a purpose which will presently appear. This last named rock arm 149 is connected by a depending link 150 to the inner end of a horizontally longitudinally swinging bar 151. The outer end of the bar 151 is pivotally connected to the lower arm of a large rock lever 152 which is supported at its center in a cross rod 153 and the upper end of this rock lever 152 is pivotally connected to a horizontal reciprocating bar 154. The front end of this reciprocating bar 154 is connected to a feeding carriage 155 which is guided for longitudinal reciprocating movement at the front end of the table 77 in any suitable manner and carries an inclined finger 156 which is adapted to engage the rear or trailing end of the blank strip 42 upon the table 77, and feed it toward the punch press when the carriage is moved rearwardly. Since the clutch 104 which actuates the train of rock levers, rock arms and links just described is closed only once for every eight, or series of punchings to be made on each blank strip, the longitudinally reciprocating bar 151 is lowered to its operative position by the link 150 only once during the same cycle of punching operations and when so lowered is moved forwardly to effect a movement of the feeding carriage 155 toward the punch press by means which are preferably constructed as follows:

At the opposite end of the machine, as best shown in Figs. 2 and 5, a crank wheel 160 is mounted on the main crank shaft of the punch press, and carries a crank pin 161 which is connected by a connecting rod 162 to a vertically reciprocating slide 163. The crank pin 161 is preferably mounted for radial movement in the crank wheel 160 to vary the throw thereof and the radial position of the crank pin is determined and adjusted by a screw 159. This slide 163 is guided for vertically reciprocating movement on rails 164 in the machine frame 43 for a purpose which will presently appear and is connected by a rod 165 with the inner end of a segmental

gear rack 166. This segmental gear rack moves longitudinally of the machine and is fixed to a shaft 167, this shaft being supported by brackets 168 projecting outwardly from the machine frame 43.

5 To permit of adjusting this segmental gear rack 166, as best shown in Fig. 33, the shaft 167 is eccentrically mounted in a pair of bearing members 169 and is keyed thereto, these bearing members being journaled in the 10 brackets 168. One of these eccentric bearing members 169 is formed to provide a toothed wheel 170, the teeth of which are engaged by a spring loaded plunger 171 having a finger knob 172 by means of which the plunger can be pulled out of engagement with the teeth of the wheel 170 and thereby permit the bearing members 169 and the segmental gear rack shaft 167 keyed thereto to be turned. 15 By reason of the eccentric mounting of the shaft 167 in the bearing members 169 it is apparent that the turning of the toothed wheel alters the center of the segmental gear rack 166 and permits of this adjustment. 20 Upon moving the toothed adjusting wheel 170 to any desired adjusted position it is held in such adjustment by the spring loaded plunger 171.

The segmental gear rock meshes with 30 teeth 173 formed in the central part of a transverse shaft 174, this shaft being journaled in bearings carried by a bearing block 175 as best shown in Figs. 5, 27, and 31. This shaft is formed with driving teeth 177 35 at its opposite ends, these teeth forming pinions which mesh with teeth 178 formed on the upper side of two shipper bars 179 mounted for longitudinal reciprocating movement on opposite sides of the punch 40 press and adjacent the sides of the path of the blank strips 42 through the punch press. These bars 179 are preferably hexagonal in cross section and are slidingly supported by blocks 180 and by the bearing block 175 for 45 the shaft 174 which shaft reciprocates these bars through motion derived from the segmental gear rack 166.

These hexagonal shipper bars 179 extend to the opposite or front end of the punch 50 press and at this end each of these bars connect with a rock arm 181 by means of a link 182, as best shown in Figs. 5, 6 and 7. These rock arms are arranged on opposite sides of the feed table 77 and are fixed to the ends of 55 a transverse rock shaft 183 carried by supporting arms 184 projecting forwardly from the machine bed. Between the supporting arms 184, depending rock arms 185 are fixed 60 to this rock shaft and are arranged on opposite sides of the longitudinal swinging bar 151 which actuates the blank strip feed carriage 155. The lower ends of these rock arms 185 are connected by a cross rod 186 which is arranged below the longitudinally swinging

bar 151 and is arranged to enter a notch 187 provided at the rear end of the bar 151.

Inasmuch as the rock arm 185 is driven directly from the main crank shaft 52 of the 70 punch press, it is apparent that it is reciprocated each time the punch press makes a punching operation or eight times to each strip of metal in the device illustrated. Since, however, the link 150 is lowered through the clutch 104, this link is lowered 75 once to every eight operations of the punch press. Hence when eight punches have been made in the blank strip 42 in the machine and another strip is ready to be fed the link 150 is lowered thereby lowering the longitudinal 80 swinging bar 151 into the path of the cross rod 186 carried by the rock arms 185 and since these rock arms 185 rock continuously the cross rod 186 enters the notch 187 in the longitudinally swinging bar 151 and moves 85 it toward the front end of the machine thereby moving the feeding carriage 155 rearwardly or toward the punch press and feeding the strip of metal on the table 77 to the punch press. As the link 150 and longitudinally swinging bar 151 are immediately elevated upon the finish of the rising movement 90 of the slide 125 supporting the end trimming blade 211 and the opening of the clutch 104 by a tappet mechanism hereinafter described 95 the driving connection between the rock arms 185 and the strip feeding mechanism is immediately broken as soon as the strip is fed to the punch press and the carriage 155 is returned to its normal position at the front or 100 outer end of the feed table 77.

The air buffer for the feeding mechanism

An air absorbing device, indicated generally at 190 is provided to prevent a violent 105 return movement of the feeding carriage 155 and its associated actuating mechanism after a blank strip 42 has been fed toward the punch press. Such violent return movement would be liable to cause the notched bar 151 110 to be thrown forward so violently as to cause its notch 187 to be placed out of alignment for the proper reception of the bar 186. Such misalignment would cause a failure of the movement of the rock arm 152 at its proper 115 period. This absorbing device 190 is arranged at the outer end of the feed table 77, as indicated at 190 and is preferably constructed as follows:

Carried by hangers 191 is a longitudinal 120 sleeve 192 which supports an air cylinder 193. In this cylinder 193 is arranged a piston 194 and a piston rod 195, the other end of this piston rod 195 being secured to a head 196 which is pivotally connected to the longitudinally movable bar 154 which connects 125 to the feed carriage 155, as best shown in Fig. 6. The piston 194, as best shown in the enlarged view Fig. 35, has a cup leather 197 and its rearward movement is resisted by the 130

air cushion built up in the outer or front end of the air cylinder 193, this end of the air cylinder being closed by a head 198. An exhaust passage 199 is provided through this head 198, the escape of air through this exhaust passage 199 being controlled by a needle valve 200 which can be opened or closed to provide any desired escape of air and hence any desired cushioning action of the absorber. When, however, the feeding carriage 155 has been practically returned to its initial feeding position, it is desirable to exhaust quickly all of the air pressure in the air absorber 190, since otherwise this air pressure or cushion might react to move the carriage rearwardly out of its normal return position at the extremity of the feeding table 77.

To provide this quick and complete exhaust of the air a second exhaust passage 201 is provided in the head 198, this exhaust passage 201 communicating with the exhaust passage 199 and being controlled by a plunger valve 202. This plunger valve 202 is normally held closed by a spring 203 which is adjustably held under tension by an adjusting screw 204 and is opened by a stem 205 which extends through a slideway provided in the head 198 and into the air cylinder 193. The movement of the piston 194 toward the head 198 is cushioned by the restricted escape of the air pressure past the needle valve 200 but when this piston strikes the stem 205 of the plunger valve 202, it opens this plunger valve and permits all of the air pressure in the air cylinder to escape quickly through the exhaust passage 201.

The releasing and latching mechanism for the feeding mechanism

After a blank strip 42 on the feed table has been fed to the punch press and the feeding carriage 155 has returned to its normal forward position, shown in Fig. 6, means are provided for positively raising the notched bar 151 clear of the cross rod 186 on the rock beams 185 so as to break the driving connection between the feeding carriage 155 and the punch press and render the feeding carriage inoperative until another strip 42 is to be fed. These releasing means also operate to positively latch the notched bar 151 against dropping so that while it is inoperative it cannot accidentally drop and cause an accidental operation of the feeding carriage 155 which would, of course, result in crumpling the blank strip 42 placed on the feeding table preparatory to being fed and possibly break parts of the machine or injure the operator. These means for releasing or rendering inoperative the feeding mechanism after a feeding stroke thereof and latching the feeding mechanism in such inoperative position are preferably constructed as follows:

As shown in Figs. 13-16, a collar 300 is keyed in the driven shaft 105 of the clutch 104, which driven shaft is oscillated once for every eight operations of the punch press as previously described. To one side of this collar 300 is pivotally secured a rod 301 which, as shown in Fig. 7, passes through an ear 302 formed on the punch press frame 43 and at its outer end is provided with a nut and washer which retain a helical spring 303 under compression against the ear 302. This spring therefore forms a return spring to insure the return movement of the driven clutch shaft 105 after the clutch has been closed to actuate the feeding and other mechanisms driven by it.

Projecting in the opposite direction from the collar 300 is a rod 304 which passes through a block 305 which block is pivotally mounted on the end of a rock arm 306. The connection between the rod 304 and the block 305 preferably comprises a collar 307 against which the block 305 is yieldingly held by a helical compression spring 308. The rock arm 306 is fastened to a rock shaft 309 which also carries a rock arm 310 at the outer end of which a block 311 is pivotally secured. This block 311 is provided with a slideway receiving a sliding rod 312. This rod projects upwardly from the block and when the clutch shaft 105 is in its inoperative or idle position, as shown in Figs. 13 and 16, this rod is in the path of the recessed end of a tappet arm 313. This tappet arm 313 is fixed to the rock shaft 88, this rock shaft being rocked each time a punching operation occurs, as previously explained.

The lower end of the sliding rod 312 is pivotally connected to one arm of a rock member 314 which is mounted on a stub shaft 105 or pin 315 projecting outwardly from the punch press frame. The opposite arm of this rock member 314 is connected to a shipper rod 316, this shipper rod at its lower end being pivotally connected to a rock arm 317 which, as best shown in Figs. 5 and 7, projects forwardly from one end of the transverse rock shaft 144.

During the retraction movement of the carriage 155 the driven clutch shaft 105 is returned to its normal position shown in Fig. 16 and the collar 300 moves the rod 304, rock arm 306, rock shaft 309 and rock arm 310 to bring the upper end of the sliding rod 312 under the tappet arm 313. The actual movement of the rod 312 to its position under the tappet arm 313 is effected by the spring 308 as hereinafter described. As this tappet arm 313 is mounted on the continuously rocking shaft 88, the tappet arm drives the sliding rod 312 downwardly which movement of the sliding rod 312 downwardly through the rock member 314, raises the shipper rod 316 and the rock arm 317 (Fig. 5) to rock the rock shaft 144 counterclockwise as viewed in Fig.

5. This movement of the rock shaft 144 is sufficient to throw its rock arm 145 and the link 146 connected thereto (Fig. 6) rearwardly beyond their dead center. Such rearward movement of the rock arm 145 and the link 146 rocks the rock arms 147 and 149 forwardly and upwardly or counterclockwise as viewed in Fig. 6 and thereby elevates the link 150 and the horizontally swinging notched bar 151 pivotally connected with the lower end of the link 150. When the notched bar 151 is raised its notch 187 is freed from the cross rod 186 carried by the swinging rock arms 185 and the driving connection between the feeding carriage 155 and the punch press is thereby broken and since this connection is broken at the same time that the feeding carriage has reached its retracted position at the front end of the feeding table 77, the feeding carriage remains in this position until the feeding mechanism is again placed in operation by the upward movement of the slotted rod 140 as described.

It is apparent that the action of the tappet arm in throwing the rock arm 145 and link 146 should be deferred until after the carriage 155 has been fully retracted. This deferred action is effected by the spring 308 which yieldingly urges the sliding rod 312 inwardly, as best shown in Fig. 7. During the first part of the advancing movement of the carriage 155, the collar 300 (Fig. 15) is moved to swing the sliding rod 312 outwardly clear of the tappet arm 313. The tappet arm thereupon comes down but does not strike the sliding rod 312 since at this time the sliding rod is inoperative. At the start of the retracting movement of the carriage 155, the collar 300 and the tappet arm 313 are moved in the reverse direction, but the reverse movement of the collar 300 merely serves to draw the sliding rod 312 against the end of the tappet arm 313, the spring 308 compressing and permitting the rod 304 to move without moving the sliding rod 312. When, however, the carriage 155 is fully retracted, the tappet arm 313 rides beyond the end of the sliding rod 312 and the spring 308 snaps the sliding rod into its position under the tappet arm 313, as shown in Fig. 16. The tappet arm 313 thereupon comes down on the sliding rod 312 and throws the rock arm 145 and link 146 rearwardly beyond their dead center so as to lock or latch the swinging notched bar 151 in its elevated position until the punch press is again ready to have another strip fed to it, as previously described.

Since the tappet arm 313 of this releasing mechanism rocks the rock shaft 144 (Fig. 6) upwardly beyond the dead center of its rock arm 145 and the link 146 connected to it, it is apparent that the horizontally swinging notched bar 151 will be positively held up and out of engagement with the rod 186 of its operating rock arms 185 since the weight of

this slotted bar 151 would merely tend to throw the link 146 and rock arm 145 further rearwardly beyond their dead center, this movement being limited by the pin 142 of the rock arm 143 engaging the lower end of the slot 141 in the slotted bar 140. The position of the link 146 and rock arm 145 above their dead center has no influence, however, on the action of the slotted bar 140 in rendering the feeding mechanism operative since the upward movement of this slotted bar 140 first throws this rock arm 145 and link 146 below their dead center and then moves these members to lower the horizontal notched bar 151 to engage the cross rod 186 of the swinging beams which actuate the feeding carriage.

After the link 146 and rock arm 145 have been rocked upwardly beyond their dead center to stop the feeding carriage in its retracted position the continued tapping of the tappet arm 313 on the upper end of the sliding rod 312 has no effect, this tapping continuing until the end of another feeding operation occurs when the tappet arm 313 again raises the horizontally swinging notched bar 151 (Fig. 6) in the manner described.

The guiding mechanism

The front or advancing end of the strip 42 being fed forwardly by the feeding carriage 155 is guided downwardly by an inclined guide plate 210 which is adjustably fixed to the main frame 43 so that it can be raised or lowered, this being effected in any well known and usual manner. This guide plate 210 guides the advancing end of the strip 42 being fed forwardly by the feeding carriage 155 between the jaws of an end trimming mechanism which is preferably constructed as follows:

The end trimming mechanism

To avoid waste of material, the maximum number of punchings are made in each strip. For this purpose the trailing end of the strip being punched is trimmed to exact length and the advancing end of the next succeeding strip is gaged and released in predetermined relation to the trimmed rear end of the strip in the press so that the strips go through the press in immediate succession and the maximum number of punchings is made in each.

The shearing or trimming blades comprise a movable blade 211 which is removably attached to the lower end of the vertically movable slide or frame 125 which, as previously described, forms part of the feeding mechanism and is moved vertically once for every eight punching operations of the punch press. This upper blade 211 cooperates with a lower fixed blade 212 which is adjustably mounted on the machine bed 43, the movable blade 211 shearing against the front side of the fixed blade so that the end of metal 213 cut from the trailing edge of the strip in the

punch press falls outside of the punch press. The frame 125 can be guided in its movement in any suitable manner, but is preferably held against an outer vertical rail 214 by gibbs 215, as best shown in Figs. 9 and 10.

To permit the piece 213 trimmed or sheared from the trailing end of the blank strip 42 in the punch press to fall through the feeding table 77, the feeding table is provided with the movable section 134 which is mounted on the upper ends of the table supporting rock arms 133 and 135 which form part of the mechanism for actuating the feeding carriage 155 as previously described. 10 This table falls downwardly and forwardly when the shearing blades 211 and 212 come together and form an opening through which the sheared end 213 falls clear of the machine. 15

It is apparent that the feeding movement 20 of the feeding carriage must not start before the shearing operation has been completed and hence the parts actuating the feeding carriage 155 through motion derived from the shearing mechanism are so designed that 25 the shearing operation is completed before the carriage 155 starts to feed the blank strip on the table 77. This is effected by the provision of the slot and pin connection 141 and 142 between the shipper rod 140 and the rock 30 arm 143.

As best shown in Figs. 6 and 8, the downward movement of the movable shear blade 211 and the movable table section 134 is practically complete before the upward 35 movement of the shipper rod 140 causes the pin 142 to engage the bottom of the slot 141 and be moved so as to effect an engagement between the longitudinally swinging bar 151 and the actuating rock arm 185. This slot 40 and pin connection 141, 142 therefore effects a delayed action of the feeding carriage 155 and secures proper synchronism in the operations.

The gaging mechanism

45 It is apparent that in the punching of continuously fed strips of blank metal that the strips must be in immediate succession and end to end, since if gaps occur, or if one strip overlapped the other the strips would be 50 out of register with the dies and imperfect punchings would be made at the ends of the strip. To prevent this, a gaging device is provided which moves into the path of the strip being fed, stops and positions it so that 55 it is arranged in predetermined relation to the trimmed rear end of the strip being punched and then releases it so that it takes a position against the trailing end of the strip in the punch press. By this means there is 60 no tendency for the blank strips to overlap, and while the feeding is positive, the strips are properly gaged regardless of variations in their length. This gage must, of course, operate only when a strip is fed or once in 65 eight punching operations of the punch press

in the punch press illustrated, and is preferably constructed as follows:

The numerals 220 and 221 represent upper and lower fixed guide shoes which project inwardly from the pedestals 124 in the direction of movement of the blank strips 42 through the press. These shoes are comparatively wide and flat and are adjustably secured to the machine frame in any suitable manner and are spaced apart a sufficient 70 distance to allow the blank strips of metal 42 to be fed between them. These shoes are also formed to provide a converging guide throat at their front ends to receive and guide the advancing ends of the blank strips being 75 fed to the punch press and each is formed to provide a transverse slot 222 which extends inwardly from the same side of each shoe.

80 Mounted for movement in and out of the slots 222 is a gage plate 223, this gage plate 85 being mounted on a swinging arm 224 which, as best shown in Figs. 9 and 10 is pivoted at 225 to an adjusting slide 226. This adjusting slide is mounted on a slotted arm 227 which projects outwardly from the pedestals 90 124 and the slide 226 is suitably bolted for movement along this arm and capable of being tightened thereon at any place so that the position of the gage plate can be altered to suit different lengths of blank strips 95 being operated on.

100 The swinging arm 224 supporting the gage plate 223 is provided with an upward extension which receives the threaded end of a link 228, the extension on the arm 224 being held between two adjusting nuts on the link 228. The other end of the link 228 is slotted as indicated at 229 and this slot receives a pin 230 of a rock arm 231 which, rock arm 105 is keyed to a rock shaft 232. This rock shaft is journaled in brackets projecting inwardly from the pedestal 124, and at one end carries a rock arm 233 which is actuated by a shipper rod 234. As best shown in Fig. 8, this shipper rod 234 extends downwardly and connects 110 with a rock arm 235 on a rock shaft 236, this rock shaft 236 being actuated by a rock arm 237. This last named rock arm is connected by a link 238 with a rock arm 239 mounted on the rock shaft 144, which, as 115 previously described is rocked at the completion of the shearing operation to effect an advancing or feeding movement of the feeding carriage 155.

120 During the normal operation of the machine, i. e. while a blank strip in the punch press is being punched and the strip feeding and end trimming mechanisms are inoperative the rock arm 143 on the rock shaft 144 is depressed as shown in Fig. 5 and consequently the gage plate 223 is held in an elevated position away from the upper face of the strip being punched by the rock arm 239 on the rock shaft 144 (Fig. 8) horizontal link 238, rock arm 237, rock shaft 236, rock 125 130

arm 235, shipper rod 234, rock arm 233, rock shaft 232, rock arm 231, slotted rod 228 and the swinging arm 224 on which the gage plate 223 is carried.

5 At the end of the shearing operation the slotted rod 140 is raised to a point where the pin 142 is engaged and this raises the rock shaft 143 and rocks the rock shaft 144 so as to rock the rock arm 239 rearwardly. This 10 movement moves the horizontal rod 238 rearwardly, elevates the shipper rod 234 and the rock arm 233 and rocks the rock arm 231 rearwardly so as to free the pin 230 and permit the slotted rod 228 to move rearwardly and the swinging arm 224 and gage plate 223 to drop. The gage plate 223 therefore drops onto the trailing trimmed end of the blank strip 42 in the punch press and as soon as this strip rides beyond the gage plate 223, the gage plate 223 drops into its operative position in the path of the blank strip 42 being fed by the feeding carriage 155. During the continued upward movement of the slotted rod 140 and continued elevation 15 of the rock arm 143 in placing the feeding carriage 155 in operation, the pin 230 travels idly rearwardly through the slot 229, the gage plate 223 being free to drop into the path of the strip being fed. The blank strip 20 42 being fed is then moved rearwardly by the feeding carriage 155 and the leading end of the same is moved over the elevated movable table section 134, under the guide plate 210, between the open blades 211 and 212 of 25 the rear end trimmer and against the gage plate 223.

Upon the completion of the retraction of the feeding carriage 155, the collar 300 on the driven clutch shaft 105 (Fig. 16) moves 30 the sliding rod 312 under the tappet arm 313 on the rock shaft 88 and this tappet arm striking the sliding rod 312 raises the shipper rod 316 and rock arm 317 (Fig. 5) and thereby rocks the transverse rock shaft 144 35 counterclockwise as viewed in Fig. 5. This counterclockwise movement of the rock shaft 144 (Fig. 8) rocks the rock arms 237 and 239 and the link 238 forwardly thereby depressing the shipper rod 234 and rock arm 233 and 40 rocking the rock arm 231 forwardly. This forward movement of the rock arm 231 causes its pin 230 to engage the front or outer end of the slot 229 in the slotted rod 228 and thereby raises the swinging arm 224 and elevates the gage plate 223 carried thereby 45 out of engagement with the advancing end of the blank strip 42 being fed to the punch press and lying on the feed table 77. The advancing end of the blank strip 42 so released thereupon drops into a position immediately in rear of the trimmed trailing end of the strip in the press. The proper timing of the mechanisms involved insures that the strips, trimmed to exact length, are fed

through the press in immediate succession and without danger of overlapping.

The advancing mechanism

After the blank strip 42 has entered the 70 punch press, means must be provided for advancing it step-by-step or from station to station each time a punching movement of the dies is effected, this advancing operation being effected during the period when 75 the dies are retracted and being preferably constructed as follows:

Below each of the hexagonal shipper rods 179, which as previously described, slide lengthwise of the punch press and in unison 80 with the punching operations, is a second rod 240 which is preferably square in cross section but is rotatably mounted in the bearing blocks 175 and 180.

Mounted on these rods at suitable intervals 85 are grippers indicated generally at 241 which grippers are secured to the shipper rods 179 and are provided with gripping elements which are actuated by the turning of the lower rod 240 to grip the upper and lower 90 sides of the blank strip of metal in the punch press at the opposite edges thereof. Means are provided for turning the lower rods 240 during the advancing longitudinal movement of the rods 179 so that the grippers 241 95 are actuated to grip the edges of the strip 42 in the punch press and advance the same. These means also turn the rods 240 to release the grippers 241 during the return longitudinal stroke of the rods 179. By this 100 means the blank strip 42 in the machine is advanced step-by-step through the machine, the length of the step being determined by the adjustment of the throw of the crank pin 161 on the crank wheel 160. These means for 105 turning the lower rods 240 to cause the grippers 241 to engage and disengage the edges of the blank strip in the punch press during the advancing and retracting movement, respectively, of the rods 179 and 240, are preferably constructed as follows:

As best shown in Fig. 32, a cam 242 is fast to the main crank shaft 52 of the punch press, the salient and receding edges of this cam being engaged by a pair of rollers 243 115 carried by the depending arms of a pair of bell crank levers 244. These bell crank levers are arranged in opposite sides of the main crank shaft 52 and the horizontal arm of each is connected by a shipper rod 245 with a rock arm 246 mounted on a longitudinal stub rock shaft 247. This stub shaft carries another rock arm 248, the two rock arms 248 on each side of the machine being connected by a cross link 249 to insure the engagement of the rollers 243 with the driving cam 242 and to insure both of the stub shafts 247 rocking in unison. Each of these stub shafts also carries a rock arm 250 which is connected by a link 251 with a rock arm 252 fast on a rock 120 125 130

shaft 253. The rock shafts 253 each extend longitudinally of the machine and are journaled in the bearing blocks 175 and 180. Between the bearing blocks 175 and 180, the 5 rock shaft 253 is journaled in a bracket 254 which can be of any suitable form but preferably is carried by the bars 179 and 240 and the rock shaft 253 and is held against sliding movement relative to the rock shaft 253 10 and the lower square rod or bar 240 and slidingly receives the longitudinally reciprocating bar 179. In this bracket a toothed wheel 255 is secured to the rotatable lower shaft 240, the teeth of this 15 wheel being engaged by a spring loaded plunger 256 carried by a swinging arm 257. This swinging arm 257 is pivotally mounted on the hub of the toothed wheel 255 and the plunger 256 can be retracted from the teeth 20 of the wheel 255 by means of a finger knob 258, thereby permitting any desired relative adjustment between the swinging arm 257 and the toothed wheel which turns the square shaft, as shown in Fig. 29, the shaft 25 240 being turned to effect this adjustment by means of a hand wheel 400 fixed to this shaft and arranged immediately adjacent the toothed wheel 255, as best shown in Figs. 29 and 30.

20 Adjacent the bracket 254, a rock arm 259 is keyed to the rock shaft and the end of this rock arm is connected to the swinging arm 257 which drives the toothed wheel 255. It is therefore apparent that as the rock shafts 25 253 on opposite sides of the machine are rocked, a similar movement is imparted to the lower longitudinal rods 240, the degree of rocking motion imparted being dependent upon the adjustment of the plunger 256 relative to the toothed wheel 255.

25 The grippers 241 are shown as being four in number, these grippers being arranged within the punch press frame. As best shown in Figs. 20—23, each of these grippers includes a pair of U-shaped supporting members 260 which are clamped against the opposite sides of the longitudinally shifting bar 179 and are movable therewith, and at their lower ends rotatably support the hubs 50 of a pinion 261. Each of these pinions is provided with a square opening which slidingly receives the lower rotatable shaft 240 so that the gripper as a whole is fast to the upper longitudinally movable bar 179 and 55 is slidingly connected to the lower rotatable bar so that upon turning this bar, the pinion 261 is also turned.

60 The supporting member 260 also supports a horizontal channeled member 262, the outer end of which is formed to provide a fixed jaw 263 which engages under the edge of the blank strip 42. This under jaw is preferably provided with a removable gripping element 264 which is milled or roughened to 65 provide a rough gripping face, this element

being replaceable as it wears. In the channel of the channeled member 262 is arranged a floating rack 265, the teeth of which engage with the teeth of the pinion 261, so that upon turning this pinion the rack is moved 70 longitudinally along its channel. A rod 266 extends through this rack and at its outer end this rack is threaded and provided with a locked nut 267 and a helical spring 268 surrounds the outer end of this rod 266 and 75 is interposed between the nut 267 and the outer end of the channeled member 263. At the inner side of the gripper, a movable jaw 269 is pivoted to the fixed jaw 263, this movable jaw being provided at its outer end with a milled under surface and being adapted to grip the upper side of the blank strip 42 so that the adjacent edge of the blank strip is firmly held between these jaws. The movable jaw 269 is moved toward and from the 80 fixed jaw 263 by a pair of toggle links 270, 271 and the pivotal connection between these toggle links 270, 271 is also connected to an operating link 272 which link 272 is connected to the inner end of the rod 266.

85 With this arrangement of the parts the operation of the grippers 271 in gripping the edges of the blank strip 42 in the machine and advancing it to its next station while the dies are withdrawn is as follows:

90 At the start of the retracting movement of the dies, the cam 242 (Fig. 32) forces the shipper rods 245 down and through the rock arm 246, rock shaft 247, rock arm 250, link 251, rock arm 252, rock shaft 253, (Fig. 29), link 260, adjustable arm 257, toothed wheel 255 and rotatable shaft 240. These shafts are thereby rotated in opposite directions and turn the pinions 261 (Fig. 21) forming part 95 of the gripper 241 in the direction to move the racks 265 outwardly. In each of the grippers 241 this outward movement of the racks 265 reacts against the spring 268 and nut 267 to yieldingly move the rod 266 outwardly. This movement of each rod 266 causes an 100 outward movement of the toggle links 270, 271 through the operating link 272 and this causes the toggle links to force the upper movable gripper jaw 269 of each gripper to move toward the lower fixed gripper jaw 263 and grip the adjacent edge of the blank strip of metal 42 being punched. It will be noted that by the employment of the spring 268 that the gripper jaws 269 and 263 are 105 yieldingly held together so that these jaws adapt themselves to variations in the thickness of the blank strip being punched and also to irregularities at the edges of the strips. If unusually thick strips 42 are being operated on, the throw of the rotating bars 240 are 110 adjusted by withdrawing the plungers 256 (Fig. 29) and moving the adjusting arm 257 with reference to the toothed wheels 255 to 115 secure the desired oscillation of the two bars 240 which actuate the grippers 241.

- As soon as the jaws of the grippers 241 have come together and gripped the edges of the blank strip 42 in the machine, the crank wheel 160 (Fig. 5), through the connecting rod 162 moves the slide 163 down and through the link 165 rocks the segmental gear rack 166 outwardly. This rocks the transverse shaft 174 with which the segmental gear rack 166 meshes and the teeth 177 formed at the outer ends of this shaft through their engagement with the teeth 178 of the longitudinally movable rods 179 (Fig. 31) moves these rods rearwardly. Since the grippers 241 are fast to these rods 179 they are moved rearwardly and carry the blank strip gripped by their jaws rearwardly the length of the throw of the longitudinally movable rods 179, this throw being determined by the adjustment of the crank pin 161 in the crank wheel 160 (Fig. 2). As soon as the blank strip 42 in the punch press has been advanced a step the gripping jaws 263 and 269 of the grippers 241 release the edges of the strip by a reverse movement of the parts, the longitudinally movable bars 179 are retracted by the continued movement of the crank wheel 160, the dies are again brought against the strip and the sequence is repeated.

30 The scrap cutter

- For convenience in handling the scrap metal or punched blanks, it is desirable to cut the punched strips into lengths. This is effected by a scrap cutter indicated generally at 275 which cuts the opposite edges of the punched strip at the places where the voids are left by the dies so that the punched strip is cut into lengths. These scrap cutters 275 are substantially similar to the grippers 241 except that knives or shearing blades are substituted for the milled gripping elements of the grippers, the scrap cutters 275 being otherwise identical in construction and operation with the grippers 241.

The scrap cutters 275 are preferably located near the rear of the punch press as shown in Fig. 27, so that the scrap lengths can fall from the machine. As shown in Figs. 24-26, the lower fixed jaw 263—a of the scrap cutter carries a removable blade 276 and cooperating with this fixed blade 276 is a movable blade 277 which is mounted on a movable jaw 269—a. This movable jaw is pivotally connected to the fixed jaw 263—a in the same manner as the movable jaw 269 of the grippers 241 and is similarly actuated by toggle links 270—a, 271—a, driving link 272—a, rod 266—a, spring 268—a, rack 265—a and pinion 261—a, this pinion being rotated by the rod 240 on which it is slidingly mounted. The fixed and movable blades 276 and 277 of each scrap cutter are arranged on opposite sides of the blank strip 42 and when the rods 240 are turned

these blades come together and cut off a length of the scrap strip in the same manner as described with reference to the grippers 241. Each of the scrap cutters is also preferably provided with a fixed hold down arm 274 70 which projects over the blank strip, as shown in Figs. 25 and 26.

The adjusting means

It is apparent that the synchronism and throws of the various mechanisms must be accurately adjusted with respect to one another and also relative to the strips being punched. These adjustments are so designed as to permit of adjusting the entire machine 80 to different sizes, lengths and thicknesses of strips and different numbers of punchings, these adjustments being preferably as follows:

The spacing and form of the dies 62, 63, 64 85 and 65 are altered by the substitution of different dies having the desired form and spacing, these dies being carried by the platens 61 and 66 which are removable from the punch press.

If more closely spaced smaller dies are used or if longer blank strips 42 are employed, a greater number of punchings will be made and the ratio between the number of punchings and the number of movements of the feeding mechanism, end trimming mechanism and gaging mechanism must be altered accordingly. Since this ratio is controlled by the number of teeth in the ratchet wheel 96 (Fig. 11) which rotates the controlling cam wheel 99 (Fig. 12), it is apparent that either by the substitution of another ratchet wheel 96 or by an adjustment of the throw of the arm 92 which drives this cam wheel, that the desired ratio can be obtained. This adjustment of the throw of the arm 92 (Fig. 11) is effected by lengthening or shortening the connecting link 90 or by moving the upper end of this link along the slotted rock arm 89 and securing it in the 105 adjusted position.

The entire end cutting and gaging mechanisms are mounted on the pedestal 124 which, as best shown in Fig. 6 is mounted for movement lengthwise of the machine bed 43 and is moved to the desired adjusted position by a screw 279 which carries a beveled gear 280 meshing with a similar beveled gear 281 on a transverse shaft 282. This shaft 282 is turned by means of a hand wheel 283 which is arranged to the exterior of the machine as best shown in Fig. 1. By turning this hand wheel, the position of the end trimming and gaging mechanisms on the pedestal 124 can be varied to suit different lengths of the blank 120 strips 42 being punched.

With different dies the blank strips 42 being punched may be required to pass through the punch press at different levels. To provide for this, the series of grippers

241 which carry the strip through the punch press are vertically adjustable as a unit. To effect this adjustment the bearing blocks 175 and 180 which support the longitudinal gripper carrying rods 179 and 240 on opposite sides of the machines are mounted for vertical sliding movement in pedestals 284 and are raised and lowered by vertical screws 285, as best shown in Figs. 5 and 31. These screws 285 are provided with beveled gears 286 at their lower ends which beveled gears 286 mesh with beveled gears on the ends of transverse shafts 288, as best shown in Fig. 31. At their corresponding ends on the same side 15 of the machine, these transverse adjusting shafts 288 carry beveled pinions 289 which mesh with beveled pinions 290 keyed to a longitudinal shaft 291. This longitudinal shaft 291 extends the length of the punch press and 20 at its front end is provided with a hand wheel 292, as shown in Figs. 1 and 7. It is apparent that upon turning the hand wheel 292 and longitudinal shaft 291, each of the transverse shafts 288 and the screws 285 actuated thereby will also be turned thereby raising or lowering the bearing blocks 175 and 180. Since these bearing blocks 175 support the rods 179 and 240 which carry the grippers 241 and the scrap cutters 275, it is apparent that a vertical adjustment of these elements is effected 30 and that the work will be carried through the punch press by the gripper 241 at the desired level.

Since both the throw of the feeding carriage 155 and the throw of the grippers 241 and the scrap cutters 275 are obtained through motion derived from the longitudinally movable hexagonal shipper bars 179, it is apparent that the adjustment of the throw of 35 these bars will effect a corresponding regulation in the feeding and the advancing mechanism. This is effected, as previously described by moving the crank pin 161 (Fig. 2) a greater or less distance from the axis of its 40 crank wheel 160 by means of the screw 159 and since the longitudinally movable hexagonal shipper rods 179 are actuated through motion derived from this crank pin 161, their throw will be varied according to the adjustment 45 of the crank pin.

As previously described, the gripper jaws 263, 269 (Fig. 21) can be varied in their movement to be adapted to various thicknesses of metal blanks 42 by the regulation of the position 50 of the arm 257 (Fig. 29) with reference to the toothed wheel 255. This is effected by withdrawing the plunger 258 (Fig. 30) and turning the hand wheel 400 to position the shaft swinging arm 257 and then re-engaging 55 the plunger with the teeth of the toothed wheel 255. Since these elements form part of the mechanism for opening and closing the gripper jaws 263, 269, it is apparent that by withdrawing the plunger 256 the arm 257 can 60 be given any desired throw and hence effect

any desired degree of opening or closing movement of the gripper jaws 263, 269.

The jaws 263, 269 (Fig. 21) of the grippers 241 and the jaws 263a and 269a of the scrap cutters 275 are preferably made sufficiently 70 long to accommodate blank strips 42 of different widths so that no adjustment is ordinarily required for feeding blank strips of usual widths. When such adjustment is required, however, the channel member 262 of each gripper and scrap cutter is held in place by set screws 401 so that upon loosening these set screws 401, all of the grippers and scrap cutter can be moved bodily inwardly or outwardly so as to be spaced closer or farther apart and hence receive between them narrower or wider blank strips 42. With such adjustment, of course, a readjustment of the relation between the swinging arm 257 (Fig. 29) and its toothed wheel 255 must be made 75 to insure the proper gripping of the jaws of each gripper 241 and the proper cutting by the blades of each scrap cutter 275.

Operation

In the following description of the complete operation of the machine embodying the present invention, I shall assume the same to be running and operating on a continuous stream of blank strips 42 fed to it.

In the running position, the clutch 68 (Figs. 3 and 34) is closed and motion is transmitted to the main crank shaft 52 of the punch press from the motor 44 (Fig. 2) through the pulley 45, belt 46, wheel 48, countershaft 49, 100 clutch 68 (Fig. 34) pinion 50, large driving gear wheel 51, and main crank shaft 52 of the punch press (Fig. 5).

If the machine is to be stopped, the operator moves either the hand lever 76 at the rear end of the feeding table 77 (Fig. 1) or the hand lever 78 at the front end thereof, these hand levers being operatively connected by the rod 79. Swinging these hand levers opens or closes the clutch 68 through the rock shaft 75 (Fig. 34) rock arm 74, link 73, rock arm 72, rock shaft 71, rock arm 70 and the shipper bar 69 which actuates the clutch 68.

The rotation of the main crank shaft 52 of the punch press raises and lowers the movable platen carrier 54 which is hung on the cranks 53 of the main crank shaft and thereby reciprocates the movable male dies 62 and 63 carried by the movable platen 61 toward and from the fixed female dies 64 and 65 mounted on the bed of the machine, thereby making successive punchings in the blank strip 42 as it is fed step-by-step through the punch press by the grippers 241 during the idle movement of the movable dies 62 and 63.

During the first part of the retracting movement of the male dies the cam 242 on the main crank shaft 52 (Fig. 32) swings 100

the horizontal arms of the bell crank levers upwardly thereby raising each of the shipper rods 245 and rocking its associated rock lever 246, stub rock shaft 247, rock arm 250, link 251, rock arm 252 and rock shaft 253. This rocking movement of each of the longitudinal rock shafts 253 (Fig. 29) rocks its associated rock arm 259 downwardly and through the link 260 and adjustable rock

- 10 arm 257, rocks the toothed wheel 255 and longitudinal squared rock shaft 240. These squared rock shafts 240 extend the full length of the punch press along the opposite sides of the path of the blank strips 42 and pass 15 through the square openings in the pinions 261 of each gripper 241 (Fig. 21). This rocking movement of the pinion 261 of each gripper moves the rack 265 outwardly, compresses the spring 268 and moves the rod 266 20 outwardly. This draws the toggle links 270, 271 outwardly through the link 272 and forces the movable gripper jaw 269 against the upper side of the edge of the blank strip 42, the under side of the edges of the strip 25 being engaged by the lower fixed jaw of each gripper 241.

Each of the grippers with their jaws engaged with the opposite edges of the blank strip 42 is then moved rearwardly one step 30 by the crank wheel 160 (Fig. 2) which is mounted on the end of the main crank shaft 52. The adjustable crank pin 161 of this crank wheel 160 raises the connecting rod 162, raising the slide 163 (Fig. 5) moving the 35 segmental gear rack 166 rearwardly through the link 165 and rotating the transverse shaft 174 counterclockwise as viewed in Fig. 5. This movement of the shaft 174 (Fig. 31) causes its toothed ends 177 to draw the 40 toothed part 178 of the hexagonal longitudinally movable shipper rods 179 rearwardly. The grippers 241 are fast to these hexagonal longitudinally movable rods 179 (Fig. 21) and hence this movement of these rods draws 45 the grippers 241 with their jaws 263 and 269 engaged with the edges of the blank strip 42 rearwardly and consequently advances the strip a distance dependent upon the adjustment of the crank pin 161, (Fig. 2).

- 50 Upon completion of the advancing movement of the grippers 241, the cam 242 (Fig. 32) moves the bell crank levers 244 to depress the shipper rods 245 and open the movable jaws 269 (Fig. 21) of the grippers 55 241, the operation of the connecting parts being the reverse of that described with reference to the closing movement of the jaws 263 and 269.

As soon as the jaws 263 and 269 of the several grippers 241 have opened the crank pin 161 of the crank wheel 160 (Fig. 5 depresses the connecting rod 162 and slide 163, thereby moving the hexagonal longitudinally movable shipper rods 179 to their original forward position, the movement of the

connecting parts being the reverse of that described with reference to their forward operative movement. As these hexagonal rods 179 (Fig. 21) carry the grippers 241, these grippers are also carried rearwardly by the 70 rearward movement of these rods.

As the scrap strip is discharged from the punch it is cut into lengths for convenient handling by a pair of scrap cutters 275 arranged on opposite sides of the machine (Fig. 75 27) and severing the narrow edge parts of the scrap strip made by the punching. These scrap cutters (Figs. 24-26) are substantially identical with the grippers 241 except that blades 276 and 277 are mounted on the 80 movable and fixed jaws 263-a and 269-a in the scrap cutters instead of the milled gripping elements as in the grippers 241. These scrap cutters 275 therefore operate in unison with and in the same manner as the grippers 85 241, the blades on the scrap cutters operating to sever the scrap strip instead of gripping the same.

The strips are fed in a continuous stream, the advancing end of the strip being fed being 90 gaged so as to be positioned immediately in rear of the trailing end of the strip in the punch press. It therefore follows that the strip being punched and forming the gage must be of an exact length since otherwise the 95 succeeding strip would be fed out of register with the dies and imperfect pieces punched at the front and rear ends of it, and all trailing strips, gaged by it. Before a strip 42 is fed against the rear end of the strip 42 in the 100 punch press the strip in the punch press is cut to an exact length by the vertical movement of the co-operating blades 211 and 212 (Fig. 10) of the end cutter, the movement of 105 these blades being effected by the crank pin 85 (Fig. 5) on the main crank shaft 52, connecting rod 86, rock arm 87, (Fig. 13) rock shaft 88, rock arm 109, link 110, clutch 104, clutch driven shaft 105, rock arm 120, universal link 121, rock arm 122 (Fig. 10) transverse rock 110 shaft 123, rock arm 126, link 127 and the vertical movable slide 125 which carries the movable end trimming blade 211 and moves it toward the fixed end trimming blade 212 so as to shear the end 213 of the strip 42 in the 115 punch press and trim this strip to an exact length.

The members of this train preceding the clutch 104 are rocked every time the main 120 crank shaft 52 is rotated and a punching operation occurs. As the end trimming operation occurs once for each strip or once to that number of punchings made in each strip thirteen being used as an example, the closing of the clutch 104 is effected only once for 125 every such number of punching operations by the arm 89 (Fig. 11) which is fixed to the rock shaft 88 and through the adjustable link 90 rocks the ratchet arm 92 which is loosely mounted on the shaft 97 and also rocks the 130

dog 95 thereon thereby turning the ratchet wheel 96 to effect one rotation of the ratchet wheel shaft 97 for every thirteen, or other number corresponding to the number of punchings made in a strip, for each oscillation of the arm 89. By this means the tooth 100 of the cam wheel 99 (Fig. 18) fixed to the ratchet wheel shaft 97 moves the lower arm of the bell crank lever 102 downwardly once in every thirteen punching operations and withdraws its tooth 118 from engagement with the sliding coupling key 115 (Fig. 14) and permits this key to couple the rocking driving sleeve 106 with the collar 111 fixed to the driven clutch shaft 105 whereby one out of thirteen rocks of the sleeve 106 is imparted to the driven clutch shaft 105 after which the projection 100 on the cam wheel 99 (Fig. 18) rides over the bell crank lever 102, and permits the spring 103 to move the bell crank lever 102 to open the clutch 104.

At the same time that the shearing blades 211 and 212 come together to trim the rear end of the blank strip 42 in the punch press and trim this strip to an exact length, the movable section 134 of the feeding table (Fig. 8) is also depressed through the link 129 connecting the movable blade slide or frame 125 and the rock arm 130, rock shaft 131, rear table supporting arm 133 and front table supporting arm 135. This depression of the movable table section 134 with the end trimming blade 211 forms an opening through which the end 213 trimmed from the strip 42 in the punch press falls through the machine.

During the final downward movement of the table section 134, the rock shaft 136 is rocked clockwise as viewed in Fig. 8 this movement raising the slotted bar 140 and causing its slots 141 to ride along the pin 142. At the end of the depressing movement of the table section 134 and pin 143 reaches the lower end of the slot so that this pin is raised, raising the rock arm 143 and depressing the rock arm 145, link 146, rock arms 147 and 149, and swinging notched bar 151. This movement therefore lowers the notched bar 151 into the path of the cross bar 186 of the rock beams 185. These rock beams 185 are rocked in unison with the punching operations through the crank wheel 160 on the main punch press crank shaft 52 (Fig. 2) crank pin 161, connecting rod 162, slide 163, connecting rod 165, segmental gear rack 166, central teeth 173 on the transverse shaft 174 (Fig. 31) end teeth 177 on this shaft, teeth 178 on the horizontal movable hexagonal shipper rods 179, links 182 at the opposite ends of this rock (Fig. 1) and rock beans 181 which are connected to the rock shaft 183 in which the rock arms 185 are mounted. It therefore follows that when the horizontally swinging notched bar 151 is lowered at the end of the lowering movement of the table section 134 (Fig. 6) that the notch

187 engages the cross rod 186 at the lower ends of the rock beams 185 and the notched bar is moved forwardly or toward the outer end of the feed table. This movement of the notched bar 151 through the rock beam 152 and bar 154 moves the carriage toward the rear end of the machine and starts to move the blank strip 42 on the feed table toward the punch press. 70

At the same time the gage plate 223 (Fig. 8) drops into its operative position as the rock shaft 144 is rocked clockwise, as viewed in Fig. 8, to drop the notched bar 151 into engagement with the cross rod 186 to effect a feeding movement of the feeding carriage 155, the rock arm 239 is similarly rocked, moving the rod 238 toward the rear of the machine, rocking the rock arm and shaft 237, 236, and 235, raising the shipper rod 234 and rocking the rock arm 233 upwardly and the rock arm 231 toward the rear of the machine. This movement of the rock arm 231 causes its pin to release the slotted rod 228 in which it rides, thus permitting the swinging arm 224 to drop, thereby permitting the gage plate 223 carried thereby to drop onto the trailing end of the blank strip 42 in the machine as shown in Fig. 8. 90

While the feeding carriage is being moved to feed the blank strip 42 on the feeding table, the frame carrying the movable end trim blade 211 is raised and the movable table section 134 connected therewith is also raised, this movement being effected by the return oscillation of the driven clutch shaft 105. As the blank strip 42 on the feeding table is advanced by the feeding carriage, its advancing end is therefore guided over the movable section 134 of the feeding table, under the guide plate 210, between the blades 211 and 212 of the end trimmer, and against the gage plate 223 in its path, as shown in Fig. 10. 105

The feeding carriage is then retracted by the reverse swing of the rock beams 185 (Fig. 6) the cross rod 186 being held in engagement with the notch 187 in the bar 151 until the completion of the return movement of the carriage 155. 110

The danger of this bar 151 accidentally jumping out of engagement with the cross rod 186 until the full return of the carriage is prevented by the air buffer 190 which has its piston connected to the bar 154 actuating the carriage and its cylinder supported from the feeding table 77, (Fig. 6). The return movement of the piston 194 with the carriage 155 is resisted by the restricted exhaust formed by the needle valve 200 (Fig. 35) controlling the exhaust through the passage 199. When the piston 194 has practically reached the end of its return stroke, however, it moves the plunger stem 205 and opens the valve 202 which permits a complete and quick exhaust through the passage 201. By this means there is no compressed body of air 120 125 130

retained which body of air would react to move the carriage after it has been returned to its retracted position and its connection with the rock beams 185 broken, (Fig. 6).

- 5 During the return movement of the carriage to its retracted position, the driven clutch shaft 105 is returning to its normal position, shown in Fig. 16 and the collar 300 moves the rod 304 and rock arm 306, rock shaft 309 and rock arm 310 inwardly. At 10 the same time the tappet arm 313 is rising, but until it has risen, this movement of the collar 300 merely moves the sliding rod 312 against the end of the tappet arm 313 and compresses the spring 309, as shown in Fig. 15. When, however, the tappet arm 313 clears the sliding rod, the spring 308 snaps the sliding rod 312 under the tappet arm 313 and on the next downward movement of the tappet arm 313 it drives the sliding rod 312 20 downwardly which movement of the sliding rod 312 downwardly, through the rock member 314 raises the shipper rod 316 and the rock arm 317 (Fig. 5) to rock the rock shaft counter-clockwise as viewed in Fig. 5. This movement of the rock shaft 144 is sufficient to throw its rock arm 145 and the link 146 connected thereto (Fig. 6) rearwardly beyond the dead center. Such rearward movement of the rock arm 145 and the link 146 rocks the rock arms 147 and 149 forwardly and upwardly or counter-clockwise as viewed in Fig. 6 and thereby elevates the link 150 and the horizontally swinging notched bar 25 151 pivotally connected with the lower end of the link 150. The delayed action of the tappet arm 313, effected by the spring 308 insures against the raising of the bar 151 before the carriage 155 has completed its return movement. When the notched bar 151 is raised its notch 187 is freed from the cross rod 186—carried by the swinging rock beams 185 and the driving connection between the feeding carriage 155 and the punch press is 40 thereby broken and since this connection is broken at the same time that the feeding carriage 155 has reached its retracted position at the front end of the feeding table 77, the feeding carriage remains in this position until the feeding mechanism is again placed in operation by the upward movement of the slotted rod 140 as described. 45
- Since the tappet arm 313 of this releasing mechanism rocks the rock shaft 144 (Fig. 6) upwardly beyond the dead center of it and the link 147 connected to it, it is apparent that the horizontally swinging notched bar 151 will be positively held up out of engagement with the rod 186 of its operating rock beams 185 since the weight of this slotted bar 151 would merely tend to throw the link 146 and rock arm 145 further upwardly beyond their dead center, this movement being limited by the pin 142 of the rock arm 143 engaging the lower end of the slot 141 in the slotted bar 140.

The position of the link 146 and rock arm 145 above their dead center has no effect, however, on the action of the slotted bar 140 in rendering the feeding mechanism operative since the upward movement of this slotted bar 140 first throws this rock arm 145 and link 146 below their dead center and then moves these members to lower the notched bar 151 to engage the cross rod 186 of the swinging beams which actuate the feeding carriage.

This counterclockwise rocking of the rock shaft 144 (Fig. 8) under the releasing mechanism actuated by the tappet arm 313 (Fig. 16) at the same time swings the rod 238 (Fig. 8) toward the outer end of the feeding table thereby depressing the shipper rod 234 and rocking the rock arms and shaft 233, 232 and 231 counterclockwise as viewed in Fig. 8. With this movement the pin 230 rides along the slot 229 until it strikes the outer end thereof when it moves the slotted rod 228 toward the feeding table thereby raising the swinging arm 224 and the gage plate 223 carried thereby. This releases the leading end of the blank strip 42 on the feeding table and permits it to fall to a position immediately in rear of the trailing trimmed end of the blank strip 42 in the punch press. The first gripping fingers 241 (Fig. 27) thereupon pick up the advancing end of the strip 42 so fed and pass it step-by-step so as to effect a successive punching of the same, this operation being the normal running position with which this description of the operations started.

From the foregoing it is apparent that the present invention provides an automatic punch press for heavy gage sheet metal strips in which the blank strips placed upon the feeding table are automatically fed, gaged and positioned and carried through the punch press by means which are entirely automatic and synchronized with the operation of the punch press; the punch press is comparatively simple considering the function it performs, it is readily accessible and is easily adjustable to adapt it to different sizes and gages of blank strips to be worked upon and different sizes and types of punchings to be made. The punch press is also reliable in its operation and in particular insures the proper register of each blank strip with reference to the dies by trimming the trailing end of the preceding registered strip and gaging the strip being fed so as to fall immediately in rear of this end. The punch press will also operate continuously for a long period of time without getting out of order. The punch press is also provided with simple and reliable means for carrying the blank strips through the punch press step-by-step and for cutting the scrap strip into short lengths for convenience in handling the scrap from the punch press. The punch press is also designed to operate prop-

erly regardless of variations in the width, thickness or condition of the blank strips on which it operates.

From the nature of the invention it will be understood that the invention is not to be limited to the precise embodiment shown and described but is to be accorded the full range of equivalents comprehended by the terms of the appended claims in which the parenthetical reference numerals employed are for convenience in applying the claims to the drawings and are not intended to have any limiting effects upon the scope of the claims whatsoever.

15 - I claim as my invention:

1. A punch press including a pair of dies movable toward and from one another and a synchronized step-by-step mechanism for feeding the strip of metal to be formed between said dies, a feeding table (77) adapted to support the metal strips to be formed, primary means (155) mounted on said feeding table for feeding a succession of metal strips to said step-by-step mechanism, said step-by-step mechanism feeding said strip between said dies to have a predetermined number of punchings made in each strip and means synchronized with the movement of said dies for actuating said primary feeding means once for every said predetermined number of punching operations of said dies, including a clutch (104) forming part of the operative connection between said dies and said primary feeding means and means 35 for closing and opening said clutch once for every said predetermined number of punching operations of said dies.

2. A punch press including a pair of dies movable toward and from one another and a synchronized step-by-step mechanism for feeding the strip of metal to be formed between said dies, a feeding table (77) adapted to support the metal strips to be formed, primary means (155) mounted on said feeding table for feeding a succession of metal strips to said step-by-step mechanism, said step-by-step mechanism feeding said strip between said dies to have a predetermined number of punchings made in each strip and means for actuating said primary feeding means once for every said predetermined number of punching operations including a clutch (104) operatively connecting said primary feeding means and said dies, a ratchet wheel (96), a driving dog (95) moving said ratchet wheel and moved in unison with said dies, a cam wheel (99) actuated by said ratchet wheel and means (102) actuated by said cam wheel for closing and opening said clutch once for every said predetermined number of punching operations.

3. A punch press including a pair of dies movable toward and from one another and a synchronized step-by-step mechanism for feeding the strip of metal to be formed be-

tween said dies, a feeding table (77) adapted to support the metal strips to be formed, primary means (155) mounted on said feeding table for feeding a succession of metal strips to said step-by-step mechanism, said step-by-step mechanism feeding said strip between said dies to have a predetermined number of punchings made in each strip and means for actuating said primary feeding means once for every said predetermined number of punching operations including a clutch (104) having a rocking driven member (105) adapted to be operatively connected with said primary feeding means and a rocking driving member (106) operatively connected with said dies, a ratchet arm (92) rocked in unison with said dies, a driving dog (95) on said ratchet arm, a ratchet wheel (96) engaged by said dog, a cam wheel (99) actuated by said ratchet wheel and means (102) actuated by said cam wheel to close and open said clutch and impart one rocking movement from said driving clutch member to said driven clutch member for every said predetermined number of punching operations of said dies.

4. A punch press including a pair of dies adapted to be moved toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip and means for actuating said primary feeding means once for every said predetermined number of punching operations including a member (186) rocked in unison with said dies, a second member (151) operatively connected with said primary feeding means and means for operatively connecting and disconnecting said members once for every said predetermined number of punching operations, including a clutch (104) operatively connected with said dies and connected to move one of said members into and out of engagement with the other member, and means operatively connected with said dies for closing and opening said clutch once for every said predetermined number of punching operations.

5. A punch press including a pair of dies adapted to be moved toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip and means for actuating said primary feeding means once for every said predetermined number of punching operations including a member

(186) rocked in unison with said dies, a second member (151) operatively connected with said primary feeding means, and means for operatively connecting and disconnecting said members for every said predetermined number of punching operations, including a clutch (104) having a rocking driven element (105) adapted to move one of said members into engagement with the said other member, and a rocking driving member (106) operatively connected with said dies, a ratchet arm (92) rocked in unison with said dies, a driving dog (95) on said ratchet arm, a ratchet wheel (96) engaged by said dog, a cam wheel (99) actuated by said ratchet wheel and means (102) actuated by said cam wheel to open and close said clutch and impart one rocking movement from said driving clutch member to said driven clutch member for every said predetermined number of punching operations of said dies.

6. A punch press including a main crank shaft (52), means for rotating said crank shaft, a movable die (62) carried by the crank 25 of said main crank shaft, a die (64) cooperating with said movable die and a synchronized step-by-step mechanism for feeding the strip of metal to be formed between said dies, a second crank (160) carried by said crank 30 shaft, a connecting rod (162) connected with said second crank, a feeding table (77) adapted to support the strips of metal to be punched, a feeding carriage (155) mounted on said feeding table and adapted to feed a 35 succession of the metal strips on said table to said step-by-step mechanism, said step-by-step mechanism feeding said strip between said dies to have a predetermined number of punchings made in each strip, a member 40 (186) rocked by said connecting rod, a second member (151) operatively connected with said carriage and adapted to be connected with said first member whereby the movement of said connecting rod advances and retracts said carriage, a third crank (85) on 45 said main crank shaft, a connecting rod (86) connected to said third crank and means actuated by said last named connecting rod whereby the connection between said members is established and broken once to every 50 said predetermined number of punching operations of said dies.

7. A punch press including a main crank shaft (52) means for rotating said crank 55 shaft, a movable die (62) carried by the crank of said main crank shaft, a die (64) cooperating with said movable die and a synchronized step-by-step mechanism for feeding the strip of metal to be formed between said dies, a feeding table (77) adapted to support the strips of metal to be punched, a feeding carriage (155) mounted on said feeding table and adapted to feed a succession of the metal strips on said table to said step-by-step mechanism, said step-by-step mechanism feeding

said strip between said dies to have a predetermined number of punchings made in each strip, a second crank (160) carried by said crank shaft, a connecting rod (162) connected with said crank, a segmental gear rack (166) rocked by said second connecting rod, a shaft (174) rocked by said segmental gear rack, a longitudinally movable rod (179) reciprocated by said rock shaft, a rock beam (185) rocked by the reciprocation of said rod, a cross rod (186) carried by said rock beam, a second longitudinally movable bar (151) adapted to be moved into and out of engagement with said cross rod, means connecting said second bar to said carriage and means for connecting and disconnecting said second bar and said cross rod once for every said predetermined number of punching operations.

8. A punch press including a pair of dies adapted to be moved toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip and means for actuating said primary feeding means once for every said predetermined number of punching operations including a member (186) rocked in unison with said dies, a second member (151) operatively connected with said primary feeding means, means for operatively connecting and disconnecting said members once for every said predetermined number of punching operations, and means for varying the throw of said first member (186) to vary the throw of said primary feeding means.

9. A punch press including a main crank shaft (52), means for rotating said crank shaft, a movable die (62) carried by the crank of said crank shaft, a die (64) cooperating with said movable die and a synchronized step-by-step mechanism for feeding the strip of metal to be formed between said dies, a feeding table (77) adapted to support the strips of metal to be punched, a feeding carriage (155) mounted on said feeding table and adapted to feed a succession of the metal strips on said table to said step-by-step mechanism, said step-by-step mechanism feeding said strip between said dies to have a predetermined number of punchings made in each strip, a crank pin (161) carried by said main crank shaft, a connecting rod (162) connected with said crank pin, a member (186) rocked by said connecting rod, a second member (151) operatively connected with said carriage and adapted to be coupled with said first member whereby the movement of said connecting rod advances and retracts said carriage, means actuated through motion de-

rived from said crank shaft for operatively connecting and disconnecting said members once for every said predetermined number of punching operations and means for varying the throw of said crank pin to vary the throw of said feeding carriage.

10. A punch press including a pair of dies movable toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip, a member (186) operatively connected with said dies and moved in unison therewith, a second member (151) connected with said primary feeding means and adapted to be connected with said first member whereby the movement of said first member advances and retracts said primary feeding means, means operatively connected with said dies for coupling said members once for every said predetermined number of punching operations and means operatively connected with said dies for subsequently uncoupling said members.

30 11. A punch press including a pair of dies movable toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip, a member (186) operatively connected with said dies and moved in unison therewith, a second member (151) connected with said primary feeding means and adapted to be connected with said first member whereby the movement of said first member advances and retracts said primary feeding means, a rock shaft (144) operatively connected with one of said members and adapted when rocked in one direction to couple said members and when 40 rocked in the opposite direction to uncouple said members, means operatively connected with said dies to rock said rock shaft in the direction for coupling said members once for every said predetermined number of punching operations and means operatively connected with said dies for subsequently rocking said rock shaft in the opposite direction.

50 12. A punch press including a pair of dies movable toward and from one another and a synchronized step-by-step mechanism for feeding the strip of metal to be formed between said dies, primary means (155) for feeding a succession of metal strips to said step-by-step mechanism, said step-by-step mechanism feeding said strip between said

dies to have a predetermined number of punchings made in each strip, a member (186) operatively connected with said dies and moved in unison therewith, a second member (151) connected with said primary feeding means and adapted to be coupled with said first member whereby the movement of said first member advances and retracts said primary feeding means, a rock shaft (144), a rock arm (145) on said rock shaft, means operatively connecting said rock arm and one of said members and including a link (146) connected with said rock arm, said last named means coupling said members when said shaft is rocked in one direction and uncoupling said members when said shaft is rocked in the opposite direction, means operatively connected with said dies to rock said rock shaft in the direction for coupling said members once for every said predetermined number of punching operations and means operatively connected with said dies for subsequently rocking said rock shaft in the opposite direction thereby to uncouple said members and throw said rock arm and link beyond their dead center and latch the member actuated by said rock arm and link against movement.

60 13. A punch press including a pair of dies movable toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip, a member (186) operatively connected with said dies and moved in unison therewith, a second member (151) connected with said primary feeding means and adapted to be connected with said first member whereby the movement of said first member advances and retracts said primary feeding means, a rock shaft (144) operatively connected with one of said members and adapted when rocked in one direction to couple said members and when rocked in the opposite direction to uncouple said members, a rock shaft (88), means for rocking said shaft in unison with the movement of said dies, a clutch having a driving member (106) rocked by said last named rock shaft (88) and a driven member (105), means connecting said driven clutch member with said first rock shaft (144) whereby upon closing said clutch said first rock shaft (144) will be rocked to couple said members through motion derived from said second rock shaft (88), means operatively connected with said dies for closing and opening said clutch once for every said predetermined number of punching operations, and means for subsequently rocking said first rock shaft (144) to uncouple said members comprising a

tappet arm (313) mounted on said second rock shaft (88), a sliding member (312) operatively connected to said driven clutch member (105) and movable thereby into the path of said tappet arm, and means operatively connecting said sliding member with said first rock shaft (144) whereby upon movement of said sliding member through motion derived from said tappet arm said first rock shaft (144) is rocked in the direction to uncouple said members.

14. In combination with a punch press including a pair of dies movable toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies, means for actuating said primary feeding means in synchronism with said dies and means (190) for cushioning the return stroke of said primary feeding means.

25 15. A punch press including a pair of dies movable toward and from one another, feeding means synchronized with said dies and adapted to feed a succession of metal strips toward said dies to have a predetermined number of punchings made in each strip, gage means interrupting the feeding movement of said strips and means for releasing said gage means whereby the advancing end of said strip is arranged in predetermined relation to the trailing end of the strip being punched.

16. In combination with a punch press including a pair of dies movable toward and from one another and a synchronized step-by-step mechanism for feeding the strip of metal to be formed between said dies, primary means for feeding a succession of metal strips to said step-by-step mechanism, said step-by-step mechanism feeding said strip between said dies to have a predetermined number of punchings made in each strip, a gage plate (223) arranged between said dies and said primary feeding mechanism and movable into the path of the strip being fed, means synchronized with said dies for moving said gage plate into the path of the strip being fed and for advancing said primary feeding mechanism whereby the strip being fed is stopped by said gage plate and means for subsequently moving said gage plate out of the path of said strip and retracting said primary feeding mechanism in predetermined relation to the trailing end of the strip being punched.

17. In combination with a punch press including a pair of dies movable toward and from one another and a synchronized step-by-step mechanism for feeding the strip of metal to be formed between said dies, a feeding table (77) adapted to support the metal strips to be fed, a feeding carriage (155) mounted on said table and adapted to feed

a strip on said table to step-by-step mechanism, said step-by-step mechanism feeding said strip between said dies to have a predetermined number of punchings made in each strip, a gage plate (223) pivotally mounted to drop into the path of the strip being fed, means synchronized with said dies for releasing said gage plate to drop into the path of the strip being fed and for advancing and retracting said carriage whereby said strip being fed is moved into engagement with said gage plate by said carriage and means for raising said gage plate during the retracting movement of said carriage whereby the advancing end of said strip is disposed in predetermined relation with the trailing end of the strip being punched.

18. A punch press including a pair of dies movable toward and from one another, means synchronized with the movement of said dies for feeding a succession of metal strips end-to-end to said dies to have a predetermined number of punchings made in each strip and means synchronized with said dies to trim the trailing end of each strip to an exact length with reference to the dies whereby overlapping of said strips is prevented.

19. A punch press including a pair of dies movable toward and from one another, means for feeding a succession of metal strips between said dies to have a predetermined number of punchings made in each strip, end trimming means adapted to shear the trailing end of each strip being punched to an exact length with reference to the dies, means synchronized with said dies for actuating said end trimming means, means synchronized with said dies for subsequently advancing said feeding means and gaging means for stopping the advancing strip at a predetermined place with reference to the trimmed end of the strip being fed.

20. In combination with a punch press including a pair of dies movable toward and from one another, and a synchronized step-by-step mechanism for feeding the strip of metal to be formed between said dies, primary means for feeding a succession of metal strips to said step-by-step mechanism, said step-by-step mechanism feeding said strip between said dies to have a predetermined number of punchings made in each strip, end trimming means adapted to shear the trailing end of each strip being punched to an exact length with reference to the dies, means synchronized with said dies for actuating said end trimming means, means actuated through motion derived from said end trimming means for subsequently advancing said primary feeding means and gaging means for stopping the advancing strip at a predetermined place with reference to the trimmed end of the strip being punched.

21. In combination with a punch press including a pair of dies movable toward and

- from one another and a synchronized step-by-step mechanism for feeding the strip of metal to be formed between said dies, primary means for feeding a succession of metal strips to said step-by-step mechanism, said step-by-step mechanism feeding said strip between said dies to have a predetermined number of punchings made in each strip, end trimming means adapted to shear the trailing 5 end of each strip being punched to an exact length with reference to the dies, means synchronized with said dies for actuating said end trimming means, a gage plate adapted to be moved into the path of the strip being fed, 10 means actuated through motion derived from said end trimming means for subsequently moving said gage plate into the path of the strip being fed and advancing said primary feeding means whereby the strip being fed is 15 engaged by said gage plate and means for subsequently moving said gage plate out of the path of the strip being fed and retracting said primary feeding means. 20
22. In combination with a punch press including a pair of dies movable toward and from one another and a synchronized step-by-step mechanism for feeding the strip of metal to be formed between said dies, a feeding table (77) adapted to support the metal strips to be punched, a movable table section (134) between said feeding table and said dies, primary means (155) carried by said feeding table and adapted to feed a succession of strips from said feeding table across said 25 movable table section and to said step-by-step mechanism, said step-by-step mechanism feeding said strip between said dies to have a predetermined number of punchings made in each strip, end trimming means (211) adapted to shear the trailing end of each strip being punched to an exact length with reference to the dies, means synchronized with said dies for actuating said end trimming means, a gage mechanism including a gage plate adapted to be moved 30 into the path of the strip being fed, means synchronized with the movement of said dies for subsequently moving said gage plate into the path of the strip being fed and advancing said primary feeding means whereby the strip being fed is engaged and positioned by said gage plate and means for subsequently advancing said primary feeding means. 35
23. In combination with a punch press including a pair of dies movable toward and from one another and a synchronized step-by-step mechanism for feeding the strip of metal to be formed between said dies, a feeding table (77) adapted to support the metal strip to be punched, a movable table section (134) between said feeding table and said dies, primary means (155) carried by said feeding table and adapted to feed a succession of strips from said feeding table across said movable table section and to said step-by-step mechanism, said step-by-step mechanism feeding said strip between said dies to have a predetermined number of punchings made in each strip, end trimming means 40
24. In combination with a punch press including a pair of dies movable toward and from one another and a synchronized step-by-step mechanism for feeding the strip of metal to be formed between said dies, primary means for feeding a succession of metal strips to said step-by-step mechanism, said step-by-step mechanism feeding said strip between said dies to have a predetermined number of punchings made in each strip, end trimming means adapted to shear the trailing end of each strip being punched to an exact length with reference to the dies, means synchronized with said dies for simultaneously advancing and retracting said end trimming means and depressing and elevating said movable table section whereby the 45
25. In combination with a punch press including a pair of dies movable toward and from one another and a synchronized step-by-step mechanism for feeding the strip of metal to be formed between said dies, a primary feeding mechanism (155) adapted to feed a succession of metal strips to said step-by-step mechanism, said step-by-step mechanism feeding said strip between said dies to have a predetermined number of punchings made in each strip, an end trimming mechanism (211) adapted to shear the trailing end of each strip being punched to an exact length with reference to the dies, 50

- a gage mechanism including a gage plate (223) adapted to be dropped into the path of the strip being fed, means synchronized with said dies to advance and retract said end trimming mechanism once for every said predetermined number of punching operations, a slotted rod (140) reciprocated by said end trimming mechanism, a rock shaft (144), a rock arm (143) fast to said rock shaft and having a projection engaging said slot whereby upon the completion of the shearing movement of said end trimming mechanism said rock shaft is rocked in one direction, a member (186) rocked in unison with the movement of said dies, a second member (151) operatively connected with said primary feeding means and adapted to be coupled with said first member whereby said primary feeding means are advanced and retracted through motion derived from said first member, means actuated through the rotation of said rock shaft by said slotted rod for coupling said members, means actuated through said rotation of said rock shaft to drop said gage plate into the path of the strip being fed whereby the strip being fed is engaged and positioned by said gage plate and means actuated in synchronism with said dies for rocking said rock shaft in the reverse direction whereby said members are uncoupled and said gage plate is raised to permit the advancing end of the strip being fed to follow the trailing end of the strip being punched.
26. A punch press including a pair of dies movable toward and from one another, means for feeding a succession of metal strips toward said dies to have a predetermined number of punchings made in each strip, movable grippers (241) each comprising a fixed jaw (263), a movable jaw (269) pivoted to said fixed jaw, an outwardly extending channeled part (262), toggle links (270, 271) between the free end of said movable jaw and the inner end of said channeled part, a rack (265) in said channeled part, means operatively connecting said rack and toggle links, means synchronized with said dies for reciprocating said grippers a predetermined distance along the path of said strips and means for moving said rack to close said jaws during the advancing movement of said grippers and to open said jaws during the retracting movement thereof whereby said strips are advanced step-by-step past said dies.
27. A punch press including a pair of dies movable toward and from one another, means for feeding a succession of metal strips toward said dies to have a predetermined number of punchings made in each strip, movable grippers (241) each comprising a fixed jaw (263), a movable jaw (269) pivoted to said fixed jaw, an outwardly extending channeled part (262), toggle links (270, 271) between the free end of said movable jaw and the inner end of said channeled part, a rack (265) in said channeled part, means operatively connecting said rack and toggle links, means synchronized with said dies for reciprocating said grippers a predetermined distance along the path of said strips and means for moving said rack to close said jaws during the advancing movement of said grippers and to open said jaws during the retracting movement thereof whereby said strips are advanced step-by-step past said dies.
28. A punch press including a pair of dies movable toward and from one another, means for feeding a succession of metal strips toward said dies to have a predetermined number of punchings made in each strip, at least one shipper bar (179) arranged along the path of the strips past said dies, means for reciprocating said shipper bar a predetermined distance in unison with said dies, a gripper (241) carried by said shipper bar and including relatively movable jaws (263, 269) adapted to grip the edges of said strips, means for closing said jaws during the advancing movement of said shipper bar and opening said jaws during the retracting movement thereof whereby said strips are advanced step-by-step past said dies, and means for actuating said feeding means through motion derived from said shipper bar.
29. A punch press including a main crank shaft (52), a movable die (62) carried by the crank of said crank shaft, a die (64) cooperating with said movable die, means for feeding a succession of metal strips toward said dies to have a predetermined number of punchings made in each strip, at least one shipper bar (179) arranged along the path of the strips past said dies, a gripper (241) carried by said shipper bar and including relatively movable jaws (263, 269) adapted to grip the edges of said strips, a second crank (261) on said crank shaft, a connecting rod (162) carried by said crank, a slide (163) reciprocated by said connecting rod, a segmental gear rack (166) oscillated by said slide, a shaft (174) rotated by said segmental gear rack, said shaft (174) being provided with teeth (177) meshing with teeth (178) provided in said shipper bar whereby the rotating of said main crank shaft reciprocates said shipper bar and means for closing said jaws during the advancing movement of said shipper bar and opening said jaws during the retracting movement thereof whereby said strips are advanced step-by-step past said dies.
30. A punch press including a pair of dies

dies movable toward and from one another, means for feeding a succession of metal strips toward said dies to have a predetermined number of punchings made in each strip, at least one shipper bar (179) arranged along the path of the strips past said dies, means for reciprocating said shipper bar a predetermined distance in unison with the movement of said dies, grippers (241) carried by said shipper bar and including relatively movable jaws adapted to grip the edges of the strips being punched, a rotatable rod (240) arranged parallel with said shipper bar and operatively connected with the jaws of each gripper whereby upon turning said rod in one direction said jaws are opened and upon turning it in the opposite direction said jaws are closed and means for turning said rod in the direction to close said jaws during the advancing movement of said shipper bar and turning said rod in the opposite direction during the retracting movement of said shipper bar whereby said strips are advanced step-by-step past said dies, comprising a cam (242) synchronized with the movement of said dies, a toothed wheel (255) on said rod, a rock arm (257) loosely mounted on said rod, means operatively connecting said cam and rock arm and means for engaging said rock arm with different teeth of said toothed wheel whereby the throw of said rock arm can be varied.

31. A punch press including a pair of dies movable toward and from one another, means for feeding a succession of metal strips toward said dies to have a predetermined number of punchings made in each strip, at least one shipper bar (179) arranged along the path of the strips past said dies, means for reciprocating said shipper bar a predetermined distance in unison with the movement of said dies, grippers (241) carried by said shipper bar and including relatively movable jaws adapted to grip the edges of the strips being punched, a rotatable rod (240) arranged parallel with said shipper bar and operatively connected with the jaws of each gripper whereby upon turning said rod in one direction said jaws are opened and upon turning it in the opposite direction said jaws are closed, means for turning said rod in the direction to close said jaws during the advancing movement of said shipper bar and turning said rod in the opposite direction during the retracting movement of said shipper bar whereby said strips are advanced step-by-step past said dies, and means for moving said grippers vertically comprising bearing blocks (175, 180) supporting said rod and shipper bar and means for adjustably raising and lowering said bearing blocks.

32. A punch press including a pair of dies movable toward and from one another,

means for feeding a succession of metal strips toward said dies to have a predetermined number of punchings made in each strip, and means for advancing the strips step-by-step past said dies, including a shipper bar (179) arranged on each side of the path of said strips past said dies, means for reciprocating said shipper bar in unison with said dies, a rotatable rod (240) parallel with said shipper bar, grippers (241) carried by said rod and bar and each including a pair of cooperating jaws (263, 269) adapted to grip the edges of the strips being punched, a rack (265), means operatively connecting said rack and jaws to open and close said jaws, a pinion (261) on said rod and engaging said rack and means for turning said rod in the direction to move said pinion and rack to close said jaws during the advancing movement of said shipper bar and to turn said rod in the reverse direction to open said jaws during the retracting movement of said shipper bar whereby said strips are advanced step-by-step past said dies.

33. A punch press including a pair of dies movable toward and from one another, means for feeding and advancing a succession of metal strips between said dies to have a predetermined number of punchings made in each strip, movable scrap cutters (275) each having jaws (263-a, 269-a), and blades (276, 277) carried by said jaws and adapted to sever the scrap strips, means synchronized with said dies for reciprocating said scrap cutters with the advancing movement of said strips and retracting said scrap cutters and means for closing said jaws during the advancing movement of said scrap cutters and opening said jaws during the retracting movement thereof.

34. In combination with a punch press including a pair of dies movable toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip, a member (186) operatively connected with said dies and moved in unison therewith, a second member (151) connected with said primary feeding means and adapted to be connected with said first member whereby the movement of said first member advances and retracts said primary feeding means, means operatively connected with said dies for coupling said members once for every said predetermined number of punching operations and means operatively connected with said dies for uncoupling said members, subsequent to the complete retraction of said primary feeding means.

35. In combination with a punch press including a pair of dies movable toward and from one another and a synchronized step-by-step mechanism for feeding the strip of metal to be formed between said dies, primary means (155) for feeding a succession of metal strips to said step-by-step mechanism, said step-by-step mechanism feeding said strip between said dies to have a predetermined number of punchings made in each strip, a member (186) operatively connected with said dies and moved in unison therewith, a second member (151) connected with said primary feeding means and adapted to be connected with said first member whereby the movement of said first member advances and retracts said primary feeding means, a rock shaft (144) operatively connected with one of said members and adapted when rocked in one direction to couple said members and when rocked in the opposite direction to uncouple said members, a rock shaft (88), means for 70 connecting said driven clutch member with said first rock shaft (144) whereby upon closing said clutch said first rock shaft (144) will be rocked to couple said members through motion derived from said second rock shaft (88), means operatively connected with said dies for closing and opening said clutch once for every said predetermined number of 80 punching operations, and means for subsequently rocking said first rock shaft (144) to uncouple said members comprising a tappet arm (313) mounted on said second rock shaft (88), a sliding member (312), spring means (308) connecting said sliding means and said driven clutch member (105) said driven clutch member moving said sliding member (312) against said tappet arm (313) against the resistance of said spring means (308) and said spring means (308) reacting to move 90 said sliding member (312) into the path of said tappet arm (313) when said tappet arm (313) clears said sliding member (312) and said primary feeding means is fully retracted, and means operatively connecting said sliding member with said first rock shaft (144) whereby upon movement of said sliding member through motion derived from said tappet arm said first rock shaft (144) is rocked in the direction to uncouple said members. 95
